EARLE C. BALDON, OF RICHMOND, VIRGINIA.

AUTOMATIC STOP FOR TALKING-MACHINES.

1,095,066.

Specification of Letters Patent. Patented Apr. 28, 1914.

Application filed December 18, 1912. Serial No. 737,402.

To all whom it may concern:

Be it known that I, EARLE C. BALDON, residing at Richmond, in the county of Henrico and State of Virginia, have invented a new and useful Automatic Stop for Talking-Machines, of which the following is a specification.

My invention has reference to that class of devices or stops in the nature of attachments for talking machines, particularly disk machines, that have for their purpose to stop the disk holding turntable from further movement when the stylus reaches the end of the sound grooves in the disk record.

My invention primarily has for its object to provide an "auto-stop" device for talking machines, of a simple, inexpensive construction, and so designed that it may be readily attached to the ordinary types of disk talking machines, without requiring disk records of special construction or the rearrangement or special adjustment of the standard makes of sound boxes and the tone arms.

With other objects in view that will hereinafter appear, my invention consists of an automatic stop device for the purposes stated, and embodies the peculiar construction and novel arrangement of the parts hereinafter explained, specifically pointed out in the appended claims and illustrated in the accompanying drawing, in which:

Figure 1 is a perspective view of my invention, so much of a talking machine being shown, as is necessary to illustrate the practical application of my said invention; the sound box and the tone arm being shown at the outer or "record beginning" position in full lines and swung up with my invention in dotted lines. Fig. 2 is a similar view the sound box and stylus being at the end of the record and the brake member of the stop device, in engagement with the record disk holder. Fig. 3 is a perspective view of the several parts that show the simplest or preferred form of my invention, being the form shown in Figs. 1 and 2. Fig. 4 is a detail view of the stop "setting" arm, hereinafter referred to. Fig. 5 is a plan view, parts being in section of a slightly modified arrangement of my invention.

My invention, in its simplest form consists essentially of two main parts, a supporting arm or member 1, and a brake member 2 that includes a setting arm or handle 3, pivotally connected to the arm 1, whereby

when the said arm 1 is connected to the tone arm or sound box of the ordinary type of disk talking machines, the said brake member 2, at the proper time is caused to engage the rim of the rotary carrier or turntable on which the records are held and stop it, by frictional contact therewith.

In the drawing 4 designates a part of the cabinet of a talking machine, 5 the record carrier or turntable and 6 a disk record operatively mounted on the said carrier or table 5.

7 designates a standard bracket, 8 the tone arm and 9 the sound box, all of which may be of any well known types of talking machines now on the market.

In disk machines of the "Victrola" type, the goose-neck 10, that connects the sound box or stylus carrier with the tone arm usually has a projecting end 11, that extends through the sleeve-like bearing 12 on the outer end of the tone arm. This extension 11, in the simplest arrangement of my invention, I utilize as the support for receiving and sustaining my automatic stop devices, the general arrangement of which is shown in detail in Fig. 3 and the same comprises a tapering arm 12^a which may be a hollow tube throughout its length, but for sake of rigidity it is shown solid except at its inner end 13, which has a deep socket 14 to provide for slipping the said inner end 13 over the goose-neck extension 11, to which the extension arm 12^a is tightly secured by a split ring clamp 15, the ends of which terminate in apertured ears 16 to receive the clamp screw 17, it being apparent that the simple method of fastening my attachment to the goose-neck of the talking machine provides a quick and efficient means for applying my attachment and for connecting it with the goose-neck so that the attachments will be swung up out of the way when the tone arm and stylus is swung up and thereby provide for the desired clearance for taking off one record or applying a new record (see dotted lines in Fig. 1). The outer end of the arm 12^a is threaded to receive a threaded sleeve 18 having apertured ears 19 that form bearings for a pivot screw 20, that passes through the aperture 21 in the inner end of the lever or handle 3, held to swing in a horizontal plane and movable up out of the way with the sound box, as before stated.

Lever arm 3 has a fixed pendant member

24 preferably integral therewith, the lower end of which carries a shoe 25 of suitable yielding material. The shoe 25 and the member 24 are relatively so disposed, with 5 respect to the lever 3, that when at the down or operative position the shoe 25 is in the horizontal plane of the turntable, and is adapted, when the member 24 is moved inwardly toward the disk carrier to contact 10 with the periphery of the said carrier and act as a brake to stop the further rotation of the carrier. The hinged joint of the brake carrying lever and the arm 12^a, includes a milled nut 27 for tightening up the said 15 hinged connection to adjust the friction of the brake shoe light or heavy, as may be desired.

So far as described, the construction of my automatic stop device is such,—assuming the arm with the brake as having been 20 properly adjusted relatively to the disk to be reproduced, and the stylus as started in the record grooves, as indicated in Fig. 1—that as the sound box moves inwardly toward 25 the axis of the disk the brake member moves correspondingly inwardly, it being understood that as the stylus takes the remaining or last sound groove the brake member engages the edge of the turntable, 30 (see Fig. 2) and since, in all disks the last groove continues a short distance beyond the sound reproducing limit, it follows that 35 the adjustment of the attachment with respect to the disk can be so nicely made that the positive or final braking action on the turntable will not come into play until the record has actually completed its reproduction.

Since records are variable in the distance 40 (combined width) of the sound producing threads or grooves, it is necessary to adjust the stop to each record. This I accomplish by lowering the sound box stylus into the last groove in the record and then swinging 45 the brake carrying lever over to bring the brake shoe into close frictional contact with the turntable of the machine; so that when the stylus feeds across the sound making grooves, the brake shoe at proper time is 50 brought into contact with the turntable edge and thereby causes sufficient friction to stop it from further turning and thus prevents the scratching, scraping sounds and at 55 the same time holds the spring motor from running down.

In Fig. 5 I have illustrated a slightly modified arrangement of the invention. The supporting arm 28 has a sleeve bearing 29 and it receives the sound box goose-neck 30 60 which, in my construction, is a member and formed with a tapering extension 31 to which the brake setting lever 2 is pivotally connected, as shown.

In the modified form, Fig. 5, as also the 65 other form of Fig. 1 of my invention the

brake setting lever and the arms to which they are attached are sufficiently heavy to positively hold the stylus down in the sound grooves and from being jumped out, especially when the brake begins to frictionally engage the turntable. 70

Among the other advantages in the use of my invention it should be mentioned, that the controlling and adjustment of the brake lever 3 is done with one hand and further 75 when the hand lever 3 is raised the sound box is lifted with it, and the needle may be readily set in the last groove and the brake devices adjusted all with one hand, as stated.

31^a designates a sector that is fastened to the solid extension of the goose-neck when used with the form shown in Fig. 5, or to the arm 12^a in the form shown in Figs. 1 and 2. The sector is provided with a suitable scale and is relatively so positioned as to extend through a slot 34 in the lever handle 3, the latter having a set screw 35 for holding the lever at the desired adjustment on the sector. 80

By using a sector arranged as shown, the stopping point of a record can be determined, and the number of the stopping point on the sector can be recorded on the said record, so that ever after when the record mentioned is to be played it can be stopped without adjustment of the stopping mechanism, by simply referring to the setting number on the record and setting the stopping lever the corresponding number on 90 the sector. 95

From the foregoing taken in connection with the drawing the manner of its use, the construction and the advantages of my invention will be readily apparent. 100

While the detailed arrangement of the parts, as shown, discloses the practical application of my invention, it is understood the said details of construction may be readily modified or varied to suit the specific type of disk talking machines to which it is intended to apply them. 105

What I claim is:

1. The combination with a rotatable member, a traveling member movable over the same, said traveling member having a transverse bearing, a U-shaped member having one of its legs pivoted in said bearing, a supporting member, means for clamping said supporting member on said U-shaped member to project laterally from said traveling member and turn with said U-shaped member as said U-shaped member is turned in said transverse bearing, and a brake member pendently connected with the outer end of 110 said supporting member, and having a portion for engaging said rotatable member. 115

2. In combination with a rotatable member, a traveling member movable over the same, said traveling member having a trans- 120

- verse bearing, and a U-shaped member having one of its legs pivotally mounted in said bearing to travel with said traveling member; of a supporting member, means for removably connecting said supporting member to said U-shaped member to project in the axial line of the pivot of said U-shaped member and rotate with said U-shaped member, a bar extended in a horizontal plane and pivotally connected with the outer end of said supporting member, and a brake shoe on said bar adapted to contact the edge of said rotatable member at a predetermined time.
- 15 3. In combination with a rotatable member, a traveling member movable over the same in a horizontal plane, a member pivotally mounted in said traveling member on a pivotal axis to move at right angles to the plane of travel of said traveling member; of a supporting member, means for removably connecting said supporting member to said pivoted member to turn with the same, a bar extended in a horizontal plane and pivotally connected with the outer end of said supporting member, a brake shoe carried by said bar adapted to engage the edge of the rotatable member at a predetermined time, and means for adjustably connecting the outer end of said brake carrying bar with said supporting member for holding said bar in different positions of angular adjustment with regard to said supporting member, said last named means including a segment carried by said supporting member and co-operatively engaging said bar, and means carried by said bar for clamping said segment to said bar.
- 40 4. In combination with a rotatable member and an arm pivoted to swing in a horizontal plane over the said rotatable member, a member pivotally mounted in said arm to turn on a pivotal axis at right angles to that of the arm, of a supporting member, means for securing said supporting member to said pivoted member adjacent to its pivot, whereby said supporting member may turn with its longitudinal axis coincident with the pivotal axis of the pivoted member, an arm hinged to said supporting member, 45 a brake shoe carried by said arm and means for adjustably connecting said arm and said supporting member for holding said arm in different positions of angular adjustment with regard to said supporting member.
- 45 5. In combination with a rotatable member and an arm pivoted at one end to have its other end swing horizontally over said rotatable member, a member pivotally carried by the free end of said arm to turn on 50 an axis at right angles to the pivotal axis of the arm, a member projecting laterally from said arm carried pivoted member and held with its axis coincident with the pivotal axis of said arm carried pivoted member, a 55 brake arm pivoted to said laterally projecting member on an axis parallel to the pivotal axis of said first mentioned arm, a brake shoe carried by said brake arm, and means for adjustably connecting said brake arm and said projecting member whereby the angular distance between the same may be varied substantially as shown and described.
